UNITED STATES PATENT OFFICE.

WILLIAM SPENCER BOWEN, OF WESTFIELD, NEW JERSEY.

FEED-REGULATING APPARATUS FOR LIQUIDS.

Application filed December 24, 1926. Serial No. 156,830.

REISSUED

The invention relates to a system for controlling the supply of water or other liquid to a steam boiler or other evaporator in order that the proper quantity may be maintained therein; and it relates more especially to the high pressure type of boiler wherein great fluctuations of the temperature of the water may occur. With the very considerable differences in temperature which 5 may prevail in boilers of this type, it will be apparent that the actual volume of the water of the boiler will swell or contract appreciably in accordance with the temperature and load conditions. There is with 10 15 the present apparatus in general use, therefore, great difficulty in maintaining the proper quantity of water in the boiler since the position of the water level in the gauge glass does not afford a true index of the 20 25 quantity, or rather mass, of the water therein. Moreover, the usual gauge glass for the feed water is of necessity located at a position corresponding to the normal level of the water in the boiler and is generally at a considerable distance from the boiler floor 30 35 level, making it difficult for the operator to view the indication in the gauge glass.

The present invention has for its object a novel feed regulating apparatus for maintaining the proper quantity of water or 40 other liquid in the boiler or other evaporator for liquid and irrespective of temperature and load conditions; also, to enable indicating apparatus therefor to be located at a 45 suitable point so as to be convenient for observation.

The nature of the invention, however, will best be understood when described in connection with the accompanying drawing, 50 which is a more or less diagrammatic representation of the invention as embodied, for example, in connection with a steam boiler. Referring to the drawing, 1 designates the floor of a boiler room or the like and by 55 which is supported the boiler structure embodying the furnace portion 2 and the boiler tubes 3 and drum 4, as well as the headers 5 and 6 for the tubes. The drum 4 is supposed at all times to contain water, the 60 normal level of same being indicated at 7; and heretofore it has been the practice to control manually the supply of water to the boiler in observing the level of same in the drum through a suitable gauge glass or the 65 like, as is well understood; or, automatically, 70 by means of suitable float controlled apparatus, the float rising and falling with the level of the water in the drum of the boiler. Further expedients, such as steam and electrically controlled apparatus, have been 75 utilized for this purpose; but all depend in their operation on the actual level of the water in the drum.

In accordance with the present invention, nothing of this nature is employed; but the 80 operation, while entirely automatic, is dependent not on the actual level of the water in the boiler but rather upon its density at a predetermined temperature. That is to say, while the actual level of the water may 85 vary within comparatively large limits—the minimum, of course, being always above the safe level—the operation of the feed mechanism for supplying the water to the 90 boiler is entirely dependent upon the actual 95 mass or weight of the water in the boiler.

For example, a connection 10 is taken from the lower-most portion of the header 5, and which is also the lowest point of the water in the boiler, to one leg of a U-tube member 11 containing a mercury column 12, the other leg of the U-tube member 11 being connected through the connection 13 with the drum 4 and at a point such that it will always be open to the steam space thereof. 100 By this means, the boiler pressure will always remain equalized in the two legs of the U-tube member upon opposite sides of the mercury column 12 thereof, thus balancing this column. The water of the boiler, 105 however, will disturb this balance to an extent depending upon the hydraulic head thereof. However, the height of this column, as will be understood, is a function of the temperature of the water, so that even 110 though the actual height of the water column increases with increase of temperature, and vice versa, this difference in height will have no effect upon the position of the mercury column 12, as the actual weight of the 115 water acting thereon is not altered. Means, hereinafter described, are provided for controlling the supply of water to the boiler through the variations in the height of the said mercury column 12; and it will be 120 understood that such means are to be so adjusted that they will not be actuated until the weight of the aforesaid column of water, irrespective of its actual height in the boiler, 125 falls below a certain predetermined amount 130

and which would correspond to an unsafe level of the water in the boiler at the coolest temperature of said water employed therein.

Apparatus for affording the supply of water to the boiler may comprise any suitable well-known or special type of steam pump-control valve 15 actuated as by an electro-magnetic member as a solenoid 16 of any well-known or special design, said solenoid 10 being in turn controlled by an electric current from a suitable source of supply as the battery 17. The said solenoid and battery are to be included in circuit with the U-tube member 11, one of the leads 18 being 15 connected to the mercury column 12 and the other extending into the top of the U-tube as at the steam leg thereof and at a point normally in contact with the mercury column 12 which corresponds to a safe quantity 20 of water in the boiler. As the water in the boiler becomes depleted, it will be understood that the higher or steam leg of the mercury column 12 will gradually drop in the U-tube in accordance with the reduced 25 weight of the water in said boiler and until it no longer makes contact with the one lead 18 extending through the upper portion of said U-tube leg. Under these conditions, the solenoid responds to actuate the pump-control 30 valve for starting up the pump 19 and by which feed water is supplied through the connection 20 to the boiler, the pump continuing to operate until sufficient mass of water has been delivered to the boiler to 35 again cause the mercury column 12 to ascend in the U-tube to a point where it makes contact with the exposed lead 18. This completes the circuit to the solenoid, operating thereby the pump control valve in manner well 40 understood to shut off the supply; and, if desired, a relay alarm device indicated at 21 may be included in either of the leads 18 to give notice of the filling of the boiler.

Moreover, it will be noted that the U-tube 45 is located substantially at the lowermost part of the boiler and therefore will be conveniently situated for observation, so that the actual conditions prevailing may be observed also in the U-tube 11.

I claim:

1. The combination with evaporating apparatus, and means for supplying liquid thereto: of a pressure-responsive device exposed constantly upon opposite sides substantially to the pressure at the lowermost part of the evaporator and to the pressure in the vapor space thereof; and means operated by the prevailing difference in pressure to which said pressure-responsive device is exposed for controlling the supply of liquid. 50

2. The combination with a steam boiler, and means for supplying water thereto; of a pressure-responsive device exposed constantly upon opposite sides substantially to the pressure at the lowermost part of the 55 boiler and to the pressure in the vapor space thereof; and means operated by the prevailing difference in pressure to which said pressure-responsive device is exposed for controlling the supply of water to the boiler. 60

3. The combination with a steam boiler, and means for supplying water thereto; of a mercury U-tube member, having one leg connected to the boiler substantially at its lowermost point and the other leg constantly 75 to the steam space of the boiler; an electro-magnetic device, and a source of electricity connected to the mercury column of said U-tube member; and means controlled by said electro-magnetic device under the influence 80 of said mercury column for regulating the supply of water to the boiler. 70

4. The combination with a steam boiler, and means for supplying water thereto; of a mercury U-tube member, having one leg 85 connected to the boiler substantially at its lowermost point and the other leg constantly to the steam space of the boiler; an electro-magnetic device, and a source of electricity connected to the mercury column, the latter 90 normally closing the circuit to said electro-magnetic device; and means controlled by said electro-magnetic device under the influence of the mercury of said U-tube for regulating the supply of water to the boiler. 95

In testimony whereof I affix my signature.

WILLIAM SPENCER BOWEN.
